UNITED STATES PATENT OFFICE.

JERRY D. DECELLE, OF FORT COLLINS, COLORADO.

DESIGN FOR A DOOR-FASTENER.

SPECIFICATION forming part of Design No. 27,477, dated August 3, 1897.

Application filed June 21, 1897. Serial No. 641,716. Term of patent 7 years.

To all whom it may concern:

Be it known that I, JERRY D. DECELLE, a citizen of the United States, residing at Fort Collins, in the county of Larimer and State of Colorado, have invented and produced a new and original Design for Door-Fasteners; and I do declare the following to be a full, clear, and exact description of the same, reference being had to the accompanying drawing, forming a part thereof.

My invention relates to a new and original design for door-fasteners; and it will be fully understood from the following description and claim when taken in conjunction with the annexed drawing, in which the figure is a perspective view of a door-fastener showing my design.

Referring by letter to the said drawing, A indicates the fastener, which is made of a single piece of metal of elongated rectangular form in cross-section. Said fastener is of a general right-angled form, and it comprises

the arm *a* and the arm *b*. The arm *a* is straight throughout its length, while the arm *b* has its portion *c* contiguous to the arm *a* or ²⁵ the apex of the angle straight. This straight portion *c* of the arm *b* merges at its outer end into a concavo-convex portion *d*, which describes a left-hand curve, and said portion *d* in turn merges into a concavo-convex portion ³⁰ *e*, which describes a right-hand curve and terminates in a straight or approximately straight end *f*, as shown.

What I claim, and desire to secure by Letters Patent, is—

The design for a door-fastener as herein shown and described.

In testimony whereof I affix my signature in presence of two witnesses.

JERRY D. DECELLE.
